UNITED STATES PATENT OFFICE.

JOSEPH P. MAXFIELD, OF MAPLEWOOD, NEW JERSEY, ASSIGNOR TO WESTERN ELECTRIC COMPANY, INCORPORATED, OF NEW YORK, N. Y., A CORPORATION OF NEW YORK.

STUDIO FOR ACOUSTIC PURPOSES.

Application filed December 15, 1923. Serial No. 680,814.

This invention relates to studios used for acoustic purposes, particularly, studios for broadcasting or sound recording.

The object of the invention is to provide a studio in which sounds may be recorded or broadcasted with substantially all the natural effects that an auditor listening directly to the sounds would receive.

In accordance with the general features of the invention, a studio is provided in which the walls are so damped that the time of reverberation will be such that the sounds recorded or broadcasted will give the same acoustic effect as a person would experience in listening to the same sounds under conditions which they are generally produced. More specifically, the invention provides a studio in which the walls are damped by a hanging curtain or applying other damping material to the walls damping them to a degree such that the reverberation will be between .5 of a second and 1.0 second as determined by Sabine's method disclosed in "Collected papers on acoustics" by W. C. Sabine, Harvard University Press—1922. The damping material is preferably disposed on the walls of the studio so that there will be no large parallel reflecting surfaces opposite each other and arranged so that the sound waves cannot travel around the room and back to the pick-up device without striking a damping surface.

Experiments have shown that owing to the time of reverberation in a studio, there is produced upon the listener, a different acoustical effect depending upon whether he hears the sound with both ears or indirectly through a single pick-up device as in the case of reproducing sounds from records or broadcasting. Under the usual conditions of hearing, reverberation is always present to some extent and for this reason the effect produced on a person in a room damped so that there is no perceptible reverberation is not natural.

When a person listens to music or speech in a room he naturally uses both ears and is thereby enabled by his binaural sense to discriminate between the direct source and the reflections which constitute reverberation. He thereby subconsciously minimizes the blurring effect of the reverberation.

On the other hand when a person listens to the same sounds through a single pick-up de-

vice he no longer hears them binaurally and hence loses this ability to discriminate between the source and the reverberations and the sounds reproduced are displeasing. Since the usual recording and broadcasting apparatus is not binaural it is therefore, necessary to decrease the time of reverberation, that is, to damp each sound so that it will not "hang over" so long. If this is not done the reproduced sounds become unnatural and if the reverberation is much too large the sounds will be blurred. The more sensitive the pick-up device to the weaker sounds, the greater must be the damping.

It has been found, that by damping the walls of a studio so that the time of reverberation will be between .5 of a second and 1.0 second, as determined by Prof. Sabine's method, records made in a studio so damped will give an effect which is as near true binaural hearing as it is possible to obtain without actual binaural hearing. To most listeners this appears as natural as binaural hearing.

In the drawing Fig. 1 is a plan view of a studio embodying the invention.

Fig. 2 is an elevation of the studio.

On side walls 3, 4, 5 and 6 of the studio are hung sound-absorbing material, preferably heavy curtains 7, 8, 9 and 10, respectively, extending substantially from the ceiling 11 to the floor 12 although this is not necessary. The curtains may be hung on horizontal poles or rods 13 by any suitable fasteners which may be slidable on the rods, whereby the curtains may be adjusted to cover any desired surface to control the damping. In the arrangement shown only a portion of each wall is damped but the damping is so distributed that no large parallel undamped surfaces will be directly opposite each other. Felt or any other suitable damping material may be used in place of curtains and fixed in position if desired. The ceiling 11 as shown is not damped, but the floor 12 is substantially covered with a heavy rug 17. Smaller rugs may be used on the floor and damping material may also be used on the ceiling if desired. 18 is a source of sound such as a piano, the sound from which may be picked up by a suitable transmitter 16 connected in a system suitable for recording or broadcasting, such as the system disclosed in application

Serial No. 566,981, filed June 9, 1922, for J. P. Maxfield.

What is claimed is:

1. An acoustic studio for the conversion of sound waves into other forms of energy suitable for sound reproduction having damping means arranged so that the time of reverberation is between .5 of a second and 1.0 second. 5
2. An acoustic studio for the conversion of sound waves into other forms of energy suitable for sound reproduction, the walls damped to the extent that the time of reverberation lies between .5 of a second and 1.0 second. 10
3. In a studio for the conversion of sounds from said source into other forms of energy suitable for reproduction, means whereby the walls may be damped to render the time of reverberation to not more than 1.0 second. 15
4. An acoustic studio, damping means applied to a portion of the walls, the damped portion being in a staggered relation with the undamped portions of opposite walls. 20
5. In an acoustic studio, damping means covering portions of the walls thereof, an undamped portion of one wall being approximately opposite a damped portion of the opposite wall, and means supporting said damping means for movement parallel to the walls 25
- 30 whereby the damped area may be varied to give a time of reverberation between one-half of a second and one second.
6. In an acoustic studio having a source of sound waves, a detector for converting intercepted sound waves into electrical variations for transmission to a distance, means for controlling the quality of the sound as detected by said detector, said means comprising a plurality of sound absorbing draperies spaced at intervals around the walls of the studio so that the time of reverberation is between .5 of a second and 1 second. 35
7. In an acoustic studio including a source of sound waves and a detector, damping means applied to the walls of the studio in spaced relation whereby all reflected sound waves are intercepted at least once by said damping means before reaching said detector. 40
8. The method of treating studios for broadcasting or recording entertainments which consists in arranging damping material in and about the studio so as to give a time of reverberation between one-half of a second and one second. 45
9. The method of treating acoustic studios for broadcasting or recording entertainments which consists in absorbing sound at intervals along the walls of the studio to such an extent that the time of reverberation is between one-half of a second and one second. 50

In witness whereof, I hereunto subscribe my name this 14 day of December, A. D., 1923.

JOSEPH P. MAXFIELD.
